ICE HOLE HEATER FOR ICE FISHING
OR SIMILAR USE

Forrest W. Frownfelter, 100 16th Ave. S.,
South St. Paul, Minn.

Filed May 3, 1965, Ser. No. 85,059

Term of patent 14 years

(Cl. D81—1)

FIG. 1

FIG. 2

FIG. 3

FIG. 4

FIG. 5

FIG. 1 is a front elevational view of an ice hole heater for ice fishing or similar use, embodying my new design;

FIG. 2 is a side elevational view thereof as seen from the right side of FIG. 1;

FIG. 3 is a back elevational view thereof;

FIG. 4 is a top plan view thereof; and

FIG. 5 is a bottom plan view thereof.

I claim:

The ornamental design for an ice hole heater for ice fishing or similar use, as shown and described.
